YARN OR THREAD PACKAGE AND METHOD OF WINDING SAME.

1,141,898.

Specification of Letters Patent. Patented June 1, 1915.

Application filed May 3, 1912. Serial No. 694,938.

To all whom it may concern:

Be it known that I, JOHN V. CUNNIFF, a citizen of the United States, and a resident of Fall River, in the county of Bristol and State of Massachusetts, have invented an Improvement in Yarn or Thread Packages and Methods of Winding Same, of which the following description, in connection with the accompanying drawings, is a specification, like characters on the drawings representing like parts.

This invention relates to yarn or thread packages and to the method of winding the same.

In order that the principle of my invention may be readily understood, I shall disclose one embodiment of the yarn or thread package and the best mode known to me for producing the same.

Referring to the drawings Figure 1 represents in side elevation a wooden yarn receiver with a feeler bunch formed thereon; Fig. 2 is a similar view representing the commencement of the formation of the package with an increasing traverse and increasing gain; Fig. 3 is a similar view of the same yarn package having additional layers positioned thereon; Fig. 4 is a similar view showing the completed package; Fig. 5 is a diagrammatic representation of a portion of a single layer wound during the up portion of the traverse; Fig. 6 is a similar diagrammatic representation of a portion of a single layer wound during the down portion of the traverse; Fig. 7 is a diagrammatic representation of the upper portion of the coils of a single layer. Fig. 8 is a diagrammatic representation on an enlarged scale of a portion of a yarn package wound in accordance

with my invention, and wherein there is a uniformly increasing traverse throughout the package together with a progressively increasing gain throughout the base thereof and a uniform gain throughout the remainder thereof; Fig. 9 is a similar representation of the lower portion of a yarn package, illustrated by way of contrast, and wherein there is a uniformly increasing traverse throughout the package, but wherein the gain is uniform throughout; and Fig. 10 is a similar view of the lower portion of a yarn package, wherein there is a uniform traverse throughout, but wherein the gain is decreasing throughout the basal portion of

the package, and remains uniform through- 55 out the body thereof.

This invention relates to yarn or thread packages and to the method of winding the same.

In the practice of the invention a yarn 60 package is built upon a suitable yarn receiver by laying successive layers of yarn upon the receiver progressively from one end thereof to the other, so that the yarn may be easily withdrawn from the yarn 65 package by draft along the axis of the package, the yarn receiver being continuously rotated during the winding operation, so that the winding takes place continuously from beginning to end of the formation of the 70 yarn package.

The invention particularly relates to the formation of such a package in ring spinning and twisting frames wherein the winding is carried on simultaneously and continuously with a spinning or twisting operation.

In yarn or thread winding mechanism to which the invention relates, the coils of yarn are laid along the yarn receiver by 80 effecting a relatively oscillatory movement of a suitable yarn guide, such, for example, as the traveler of a ring spinning machine and the yarn receiver. Such movement is effected along the yarn receiver for a portion only of the length of the latter, said movement being generally termed the "traverse." The package is built by shifting the path of the relative movement progressively along the axis of the yarn receiver. This 85 shift is generally termed the "gain." In the formation of such a yarn package, a maximum diameter is reached at a point above the base due to the coöperative effect of the traverse and the gain. The portion 90 of the package from its lower end to such point of maximum diameter is termed the "base," while the conical form resulting at the other end of the yarn package is termed the "chase" or "taper" and its terminus is 95 termed the "nose" of the cop.

In accordance with my invention, the package is wound and formed with efficiency in a winding or spinning or twisting machine, and when wound in a spinning or 105 twisting machine the tension of the yarn is well controlled and the lay of the yarn is thereby benefited. In the formation of the

base of the package, the successive layers of 5
yarn are so laid one over the other until the
full diameter of the package is reached that
each bottom coil of each layer is laid safely
up and above the bottom coil of the preceding
layer (assuming the yarn receiver to be
upright and the yarn to be wound thereon
from the bottom upward), and while the
basal portion of the yarn package is so
10 characterized, preferably the same winding
effect is continued throughout the entire
length of the package. This feature of the
winding is accomplished in the disclosed em-
bodyment of the invention by increasing the
15 gain and preferably by incrementally in-
creasing the gain throughout the formation
of the base of the package. Throughout the
body of the package the gain, in the dis-
closed embodiment of the invention, is such
20 as to maintain the body of the package sub-
stantially cylindrical. In that type of the
invention disclosed the gain throughout the
body is substantially uniform.

By increasing the traverse throughout the
25 formation of the basal portion of the pack-
age, and especially by increasing the trav-
erse throughout the formation of the en-
tire package, as is effected in the disclosed
30 embodiment of the invention, each suc-
cessive layer of yarn is laid over a slightly
greater extent axially of the package than
the layer just preceding. Due to the con-
35 stant speed of the spindle or other yarn
receiver, and in ring frames particularly,
if each traverse is effected in the same per-
iod of time, then with each succeeding
40 layer the coils thereof are a little more
widely separated.

If the yarn package be formed in a ring
45 spinning frame, then by increasing the lin-
ear speed of the ring rail progressively, re-
sulting from an increasing traverse in con-
stant time, the ring rail is moved each time
50 more rapidly up and down, thereby con-
stantly decreasing the number of coils laid
at the nose or tip end of the cop, and there-
fore decreasing the lag of the traveler at
55 such place. Otherwise stated, the speed of
the traveler is maintained more nearly con-
stant and therefore the tension on the yarn
is maintained more nearly constant. Prefer-
ably the gain and the increase in traverse
60 are effected during the last portion of the
up-stroke, so that this increased speed in
linear movement of the ring rail is added
at such time. The result is that the ring
65 rail may be operated with a large increase
in the number of its reciprocations during
a given time and the yarn is wound with
much more uniform tension and with de-
creased yarn breakage.

The result of the formation of a yarn
70 package in accordance with my method is
that the increase in traverse from base to

nose gives reversely a decreasing taper from
75 nose to base, so that the yarn withdrawn
by draft axially of the package is drawn
from a surface on the package approaching
more and more nearly to a surface at right
angles to the axis of the package. There-
80 fore, as the length of yarn extending from
the surface wherfrom it is being delivered
to the point above the package, where draft
is being applied to the yarn tends to in-
crease, and ballooning of the yarn away
85 from the axis of the package tends to in-
crease, such tendency to increased balloon-
ing effect is checked because the yarn draws
from a surface approaching more and more
90 nearly to a flat surface at right angles to
the axis of the package. When the yarn
package is in a shuttle, such formation
checks the tendency of the yarn to balloon
out and contact with the sides of the shuttle,
95 and thereby decreases breakage. Further-
more, as the base of the package is reached
in the unwinding (and throughout the en-
tire package when the increase in gain is
100 established throughout the entire package)
each bottom coil of each layer (having been
safely laid by means of the increase in gain
over and above the bottom coil of the pre-
ceding layer) is permitted to be withdrawn
95 without fouling with and tending to slough
off the preceding layer. These advantages
thus secured in the unwinding are of great
practical importance in weaving where the
yarn is subjected to quick, intermittent
105 draft, reaching a speed from five to ten
yards a second.

When the yarn package is spun or formed
in a ring spinning frame, the latter is pro-
110 vided with a ring rail and with continuously
rotating yarn receivers in the form of spin-
ning spindles having bobbins of paper or
similar tubes thereon. Within the scope
of my invention, the yarn receiver may be
the bare spindle. The ring rail carrying
115 the spinning ring and travelers may con-
stitute yarn guiding means, and in accord-
ance with my invention I cause a relative to
and fro traverse movement between the yarn
guiding means and the yarn receivers, this
120 being preferably effected by imparting the
described traversing movement to the ring
rail.

By effecting a traverse of the yarn along
the receiver and by controlling the gain of
the traverses, the yarn package is built up
125 of a series of nested conical layers. The
traverse is maintained undiminished and
preferably I form the yarn package by im-
parting a regular or constant uniform in-
crease to the traverse while progressively
130 increasing the gain throughout the base of
the package, after which the gain is main-
tained undiminished and is herein repre-
sented as uniform.

The preferred constant increase in the 135

traverse, which preferably is instituted at the base of the yarn receiver and may continue either to the tip thereof or to some suitable point intermediate the base and the tip, but preferably and to secure the best results continues to the tip, effects the laying of the yarn of each layer on slightly more open lines than the preceding layer. The effect of this is, as stated, to position uniformly the yarn laid on each traverse safely past or ahead of the yarn laid by the preceding traverse. The described incremental increase of the gain safely positions the bottom coil of each layer ahead of the bottom coil of the preceding layer, and the progressive increase in the gain throughout the base assists what would otherwise be a constant gain safely to effect this object.

Inasmuch as each traverse is increased over its predecessor, each layer advances more at the top of the wind than at the bottom thereof. The effect of the described traverse and gain are to build a yarn package which at the bottom extends from the surface of the receiver to a maximum diameter without laying the bottom coil of any layer on top of or below the bottom coil of the preceding layer. A slight but continuous incremental increase in the gain together with the direct increase in the traverse lays the yarn so uniformly that the chase of the yarn package is formed with a somewhat convex line constituting a generally conical bottom in vertical cross section, until the maximum diameter of the cop or other yarn package is reached particularly if the package be wound upon a cylindrical or nearly cylindrical tube. Such maximum diameter is maintained until the top of the yarn package is reached. Thus, the increase of traverse throughout the package and the incremental increase in gain throughout the base of the package and undiminished and preferably uniform gain thereafter are constantly effective to produce and maintain a correct and advantageous form of package.

The formation of the yarn package is commenced with a certain minimum length of traverse which may be of any desired extent, as, for example, seven eighths of an inch, this traverse being gradually increased either throughout the entire length of the yarn package or to some suitable point intermediate the ends thereof, after which the package may be continued with an undiminished and preferably a uniform traverse. Preferably, however, and to secure the best results, the traverse is increased uniformly throughout the package. I have obtained excellent results by commencing the yarn package with a traverse of seven eighths of an inch and continuing the increase in the traverse to the upper end of the package, where the traverse is one and a half inches or even more. If desired, I may form a

feeler bunch at the basal end of the yarn package, particularly when the package is to be employed in a loom shuttle, and in forming such feeler bunch I impart a very short traverse, as, for example, three eighths of an inch. Such feeler bunch may be dispensed with, however. If, however, such feeler bunch be formed, then immediately after the formation thereof, I preferably abruptly increase the gain and thereafter the yarn package is preferably wound with a constantly increasing traverse throughout and a progressively increasing gain throughout the base with an undiminished and preferably uniform gain thereafter, thus securing a cylindrical body. The up and down portions of each traverse may be imparted at equal or unequal times. Preferably, however, the upward portion of the traverse occupies a less length of time than the downward portion thereof. While I have referred to the increase in the traverse as constant, I employ this term generically or broadly to refer to a preferably regular increase in the traverse, such increase occurring at a certain part of each traverse, that is, at a certain point in the formation of each upwardly wound layer, or if desired at a certain part of each of a series of traverses. I preferably impart the increase to the traverse and the increase to the gain during the up-stroke of the ring rail, and preferably near the end of such up-stroke and terminating with the end thereof.

In the formation of the yarn package in a ring spinning machine, the traverse is regularly increased and the builder cam is preferably rotated at a constant speed. Therefore, the speed of the ring rail is correspondingly increased, and inasmuch as the addition to the traverse and the addition to the gain are imparted at or near the end of the up-stroke of the ring rail, it follows that the speed of movement of the ring rail is accelerated each time toward the end of its up-stroke,—that is, when the yarn is wound upon the nose of the yarn package.

In the formation of the yarn package herein disclosed in accordance with my method, the described increase in the traverse and the described increase in the gain are imparted, in the disclosed embodiment of the invention, at or near the upper end of each up-stroke of the ring rail. Such increase in speed of the ring rail co-acts to secure the slight separation of the turns or coils of the conical layers; in other words, it prevents the superposition of one coil of a layer directly upon another coil of the same layer. Heretofore it has been impossible so to speed up the ring rail as to prevent the turns or coils of each conical layer from being superposed more or less throughout the building of the package. This necessarily resulted in the uneven delivery of

the yarn from the package in unwinding. In accordance with my invention I lay a coil of each conical layer against the side of or as close as desired to the preceding coil of that layer, but not overlying the same. Thus I secure the even paying off of the yarn.

In accordance with my invention, the incremental increase in the gain is added at or 10 during the completion of the up-stroke of the traverse, and since the increase in the traverse increases the general speed of the ring rail during the traverse, it follows that the traverse is speeded up just as the ring rail is completing its up-stroke. The result 15 is to secure the proper laying of the yarn by tending first to keep the coils of each layer laid well above each other at the top and second to reduce the number of coils 20 laid at the top,—that is, when the yarn is being wound upon that portion of the receiver of smallest diameter, and hence when 25 yarn breakage is most apt to occur. The number of coils laid at the top portion of each traverse, that is, the number of coils laid in the top portion of each layer, is reduced in the practice of my invention, inasmuch as the number of coils laid at any portion of the yarn package varies in- 30 versely as the speed of the ring rail in traversing such portion of the package. The similar increase in the speed of the ring rail at the upper portion of each traverse, that is, in the formation of the upper portion 35 of each layer, not only tends to compensate for the inherent tendency of yarn spinning mechanism to lay more winds of yarn at the upper portion of each traverse,— that is, on the portion of the yarn receiver 40 of least diameter, but it also tends to compensate for the lag of the traveler at the upper portion of the up-stroke of the ring rail with the result of less variation in the speed of the traveler, due to its lag at this 45 portion of the up-stroke. After the yarn has been coiled at the extreme tip of each layer, it is thereafter returned quickly therefrom in the laying of the next layer. Thus, 50 the yarn package is wound with reduced yarn breakage and with a more uniform tension throughout. Although I have herein referred to the increase in the traverse as constant, it is to be understood that thereby is meant a regular increase, inasmuch as in 55 practice the traverse is not increased at all instants of time during the operation of the mechanism or the carrying out of the method, but preferably only at a certain period in the formation of each layer.

60 The increment in gain in the formation of the conical layers may be such as is found desirable. In practice, I have found an initial incremental gain of about one sixtieth of an inch to produce excellent results in winding 40's. The described incre-

mental increase in the lengths of the layer need not be effected between successive traverses, but may instead be effected between successive series of traverses, said series being composed of any suitable number of 70 layers.

I have in Figs. 1 to 4 inclusive represented yarn receivers consisting of wooden bobbins but preferably of a generally tapering form and without a marked or abrupt 75 conical shoulder at the base to receive the first laid layers and to impart the desired chase or taper as largely heretofore practised. By omitting said shoulder I am enabled to spin an increased length of yarn 80 upon the receiver. It is, however, to be understood that yarn packages may be wound upon cop tubes of paper or the like or other carriers or even upon bare spindles. While the bobbin may be of any suitable shape, it is preferably of gradually decreasing diameter from substantially its lower end to its tip and may be of smaller diameter than heretofore. If desired, and especially where the yarn package is to be 90 used in a weaving shuttle, I form a bunch 2 by imparting short traverses, as, for example, about three eighths of an inch in length and involving but a few conical layers. Immediately after the formation of 95 such bunch, the gain and traverse may be abruptly increased, so that the immediately succeeding layers 3 are wound with an open coil. As here represented, the length of taper of the coils 3 is substantially seven- 100 eighths of an inch. Thereafter the gradual increase in the length of the taper commences with the described progressively increasing gain throughout the package, and at 4 in Fig. 3 I have indicated a conical 105 layer of slightly increased taper over that indicated at 3 in Fig. 2. This increasing traverse and progressively increasing gain are here represented as continued until the base of the yarn package is completed. 110 Thereafter the uniform increase in the traverse is continued and the gain is maintained uniform until the package is built up as indicated at 5 in Fig. 4 and terminates with a layer 6 here shown as of substantially one 115 and a half inches, but which may be even more. The package when thus wound is cylindrical throughout the body portion thereof. If desired, however, the maximum taper or length of layer may be 120 reached at a point more or less short of the tip end of the bobbin or even at the conclusion of the formation of the base of the yarn package, after which the layers are preferably uniform to the tip end of the 125 package. It has heretofore been an exceedingly difficult matter to unwind the bunch in the weaving operation. The yarn is exceedingly apt to break when the bunch is reached in the paying off of the yarn and 130

the weaver then discards the bunch yarn entailing much waste. In order to prevent this breakage of the yarn at the bunch, I provide the open wind 3, the yarn of which 5 pays off much more freely in the weaving operation and thereby lessens to a very great degree the liability of breakage of the yarn in said bunch, thereby reducing waste.

In Figs. 5 and 6, I have diagrammatically represented the formation of two conical layers, that represented in Fig. 5 at 7 being formed during the upward movement of the ring rail or other guide, and that represented in Fig. 6 at 8 being formed in the 15 succeeding downward movement. These figures are merely diagrammatic and are not intended to represent the actual number of coils in either layer. As will be noted, however, and in this respect the representation 20 is substantially correct, the coils shown in Fig. 5 are inclined and are much fewer in number than the coils shown in Fig. 6, which are substantially horizontal. In both cases, however, the coils are open, such open 25 wind being more apparent in Fig. 5 because fewer coils are laid during the upward movement of the ring rail, which is toward the drawing rolls and consequently rapid, than are laid during the downward movement, which is away from the drawing rolls 30 and consequently slower, because of the greater strain upon the yarn. In either case, the coils may be in actual contact or may be spaced apart, but do not overlie each other. 35 In order to secure the best results the coils are spaced apart a suitable distance as, for example, one-sixteenth of an inch in the up-portion of the traverse and one-quarter of an inch in the down-portion thereof in fine 40 yarns and one-quarter of an inch in the up-portion of the traverse and one-half of an inch in the down-portion of the traverse in coarse yarns. The result is that the coils of 45 two consecutive layers do not lie in parallelism but cross each other at an angle so that in unwinding any layer, any coil thereof cannot effect the sloughing off of another coil of such layer. Inasmuch as the conical layers formed upon upward movements of 50 the ring rail are preferably all laid in equal periods of time and the supply of the drawing rolls continues constant, it follows that the coils of the longer conical layers are 55 spaced apart more widely than are those of the shorter conical layers.

In Fig. 7, I have diagrammatically indicated the formation of the upper coils of one of the layers of the yarn package. It will be observed that the coils indicated at 60 14 are fewer in number and more widely spaced than the coils indicated at 15. Thus the tip portion of each layer is characterized by more widely spaced coils than the remaining portion of such layer; whereby 65 the number of coils at the tip portion of

each layer is reduced and the yarn or thread is quickly traversed away from the said tip into the body portion of the succeeding layer. The coils 14 are thus laid at the upper end of each traverse, that is, at the upper end of the formation of each upwardly wound layer, and upon that portion of the 70 yarn package already formed which is of the least diameter and upon the yarn receiver itself.

In Fig. 8, I have diagrammatically represented a yarn receiver 16, which is preferably a paper cop tube. The basal layer 17 is laid with a minimum length of traverse and the succeeding layers in the base up to the 75 point 18 are laid with a uniformly increasing traverse and with a progressively increasing gain. I have not herein represented all the layers which make up the basal portion of the package, the illustration being 80 diagrammatic for the sake of clearness. Throughout the body portion 19 of the package, the traverse uniformly increases and the gain is maintained uniform or substantially uniform. The basal portion of 85 the package is convex in shape, this being a characteristic of a package wound upon a cop tube with a progressively increasing gain in accordance with my invention. The said body portion 19 of the cop tube is cylindrical in shape, this being a characteristic of a package wound with a traverse uniformly increasing from the initial layers 90 throughout the package and with a gain which progressively increases throughout 95 the base, and is thereafter maintained uniform or substantially uniform,—that is to say, one in which the gain after the completion of the base is maintained undiminished.

In Fig. 9, by way of contrast, I have illustrated a package wound upon a cop tube 20, the initial layer 21 being laid by a minimum traverse. The gain throughout the basal portion of the package, that is, to the point 22, is uniform, and throughout the body 100 portion 23 of the package both the traverse and the gain uniformly increase. It will be noted that the basal portion of the package 105 is conical, this being characteristic of a yarn package wound upon a cop tube with a uniform gain in the base.

In Fig. 10, I have, by way of contrast, represented a yarn package wound upon a cop tube 24. In said package, the initial layer 25 is laid with a minimum traverse 110 and the gain throughout the remainder of the base to the point 26 is a decreasing gain. Thereafter, throughout the body portion 27 the gain is uniform. It will be observed that in this package, the shape of the basal 115 portion thereof is concave, this being a characteristic of a yarn package wound upon a cop tube with a decreasing gain throughout the basal portion thereof.

From the foregoing description, it will be 120

6 evident that the yarn or thread package is wound with an increasing gain and preferably with a progressively increasing gain throughout the base of the package and is then continued uniformly throughout the body or is 5 maintained undiminished. The traverse is preferably uniformly increased throughout the package. Preferably the increase in the traverse is continued throughout at least the 10 formation of the basal portion of the package, and in the most accepted form of the invention is continued throughout the formation of the entire package.

While I have herein referred to the upwardly and downwardly wound layers, it is 15 evident that these terms refer merely to that position in which the yarn package is customarily wound. It is, of course, to be understood that the yarn package may be 20 wound or formed in any suitable position.

It is of extreme importance that the initial traverse be of the minimum length, thus causing the first laid layer to be the shortest, and that these layers gradually 25 increase in length, since thereby in the unwinding of the cop in the weaving operation, the length of layer gradually becomes less and less from the tip of the cop toward the base, and hence there is increasingly less 30 friction and resistance or drag to the unwinding of the yarn of the successive layers as the distance increases between the eye of the shuttle and the point at which the yarn leaves the bobbin or other package carrier.

35 Since the drag thus becomes proportionately less as the distance between the yarn mass and the eye of the shuttle increases,—that is, since the friction and drag opposed to the unwinding of the yarn in the weaving 40 operation, are inversely proportional to the distance of each layer from the feeding eye of the shuttle, because of the increasingly greater length of the layers toward the tip of the bobbin or other carrier, there is effected a substantially even tension on the 45 yarn as laid in the cloth. If the winding begins with a minimum traverse, but with a gain of the full or ultimate value, the result would be that the early layers or traverses would be too long, and the desired results as regards evenness in the yarn tension 50 would not be secured. By providing, however, a minimum gain as well as a minimum traverse, the ideal condition is secured, and by 55 increasing the traverse and the gain, the uniformity of tension is not impaired. This result is secured by increasing the gain and more especially by progressively increasing the gain.

60 The ideal condition is presented by progressively increasing the gain from the minimum, inasmuch as I thereby, in the early layers, obtain very short traverses with the advantages above set forth, and at 65 the same time each layer begins safely above

the commencement of the preceding layer. Furthermore, inasmuch as I start with a minimum traverse and a minimum gain, the drag due to the distance between the spinning ring and the surface of the top tube or bobbin is not such as to prevent proper winding. If the initial traverse and gain were, in their aggregate, long, then the effect of the drag would be such that the yarn could not be properly wound. Furthermore by commencing with a minimum aggregate traverse and gain, I am enabled to reach the full diameter of the yarn package more quickly, and hence more yarn is wound onto the package at its base, without, however, obtaining longer traverses at this point. In my yarn package, as the yarn is unwound from the base toward the point of any layer, the turns of the yarn are found to be separated, thus preventing one turn of yarn 70 pulling off another, which is not true of 75 yarn packages with which I am familiar.

80 In practice, it is unnecessary to "clean" the bobbin after weaving, since the entire 85 yarn winds off. This is not true of other 90 winds with which I am familiar. I have also been able to dispense with the conical 95 form of the bobbin at its base usually used heretofore to start the spinning, and hence I am enabled to wind a correspondingly additional amount of yarn on the bobbin.

100 In practice, I have discovered that the initial short layers wound in accordance with my invention constitute in themselves a very effective "bunch," and that it is not necessary to have a special "bunch." After forming such substitute for a bunch, the winding can proceed in the same manner, whereas in most bunch-forming winds with 105 which I am familiar, after the formation of a special bunch, there is a "skip" upward or downward to begin the main winding. Furthermore a satisfactory bunch creates a strain or drag on the yarn wound below the bunch every time the yarn unwinds past and in contact with the bunch, and this creates unevenness in the tension and tends to break the yarn. I am enabled to wind the yarn upon the carrier with even tension from end to end. By decreasing the friction, as hereinbefore set forth, I am enabled to use a heavier traveler, which is a desideratum, inasmuch as the heavier the traveler, the 110 tighter the wind.

115 Having thus described one illustrative embodiment of my invention and the best method known to me for practising the same, I desire it to be understood that although specific terms are employed, they are used in a generic and descriptive sense 120 and not for purposes of limitation, the scope of the invention being set forth in the following claims.

Claims.

1. A yarn or thread package characterized 130

5 by a receiver, and a plurality of nested layers, each consisting of a plurality of coils, the basal layers of the package being of minimum length, the subsequent layers being progressively shifted along the receiver by amounts which progressively increase throughout the base of the package, the layers of said package being of uniformly increasing length throughout the package, the 10 amount of yarn or thread coiled at the tip end of the respective layers successively diminishing from the basal end to the tip of the package.

2. A yarn or thread package characterized by a receiver and a yarn mass wound thereon having tapering ends and a cylindrical body, said yarn mass consisting of a plurality of nested layers each consisting of a plurality of coils, the basal layers of the 20 package being of minimum length, the subsequent layers being progressively shifted along the receiver by amounts which progressively increase throughout the base of the package, the layers of said package being of uniformly increasing length throughout the package, the amount of yarn or thread coiled at the tip end of the respective layers successively diminishing from the basal end to the tip of the package.

3. A yarn or thread package characterized by a receiver and a plurality of nested layers, each consisting of a plurality of coils, the basal layers of the package being of minimum length, the subsequent layers being progressively shifted along the receiver by amounts which progressively increase throughout the base of the package, the lowermost coil of each layer being laid above the lowermost coil of the immediately preceding layer, the layers of said package being of uniformly increasing length throughout the package, the amount of yarn or thread coiled at the tip end of the respective layers successively diminishing from the basal end to the tip of the package.

4. A yarn or thread package characterized by a receiver and a plurality of nested layers, each consisting of a plurality of coils, the basal layers of the package being of minimum length, the subsequent layers being progressively shifted along the receiver by amounts which progressively increase throughout the base of the package, and which substantially uniformly increase throughout the remainder of the package, the layers of said package being of uniformly increasing length throughout the package, the amount of yarn or thread coiled at the tip end of the respective layers successively diminishing from the basal end to the tip of the package.

5. A yarn or thread package characterized by a receiver and a yarn mass wound thereon having tapering ends, and a cylindrical body, said yarn mass consisting of a plu-

rality of nested layers each consisting of a plurality of coils, the basal layers of the package being of minimum length, the subsequent layers being progressively shifted along the receiver by amounts which progressively increase throughout the base of the package, and which substantially uniformly increase throughout the remainder of the package, the layers of said package being of uniformly increasing length throughout the package, the amount of yarn or thread coiled at the tip end of the respective layers successively diminishing from the basal end to the tip of the package.

6. A yarn or thread package characterized by a receiver and a plurality of nested layers, each consisting of a plurality of coils, the basal layers of the package being of minimum length, the subsequent layers being progressively shifted along the receiver by amounts which progressively increase throughout the base of the package, the layers of said package being of uniformly increasing length throughout the package, the tip portion of each layer being characterized by more widely spaced coils than the remaining portion of said layer, whereby the number of coils at the tip portion of each layer is reduced, and the yarn or thread is quickly traversed away from the said tip into the body portion of the succeeding layer.

7. A yarn or thread package characterized by a receiver and a plurality of nested layers, each consisting of a plurality of coils, the basal layers of the package being of minimum length, the subsequent layers being progressively shifted along the receiver by amounts which progressively increase throughout the base of the package, and which substantially uniformly increase throughout the remainder of the package, the layers of said package being of uniformly increasing length throughout the package, the tip portion of each layer being characterized by more widely spaced coils than the remaining portion of said layer, whereby the number of coils at the tip portion of each layer is reduced and the yarn or thread is quickly traversed away from the said tip into the body portion of the succeeding layer.

8. That method of winding yarn or thread into a package which consists in imparting a minimum to and fro relative traverse movement to a yarn receiver, and a yarn guide for a portion only of the length of the former, in order to form the initial layer of the package, progressively shifting the path of said traverse movement along the receiver by amounts which progressively increase throughout the basal portion of the package, uniformly increasing said relative traverse movement throughout the package, and successively diminishing from the basal

end to the tip of the package the amount of yarn or thread coiled at the tip end of the respective layers thereof.

9. That method of winding yarn or thread into a package which consists in imparting a minimum to and fro relative traverse movement to a yarn receiver and a yarn guide for a portion only of the length of the former, in order to form the initial layer of the package, progressively shifting the path of said traverse movement along the receiver by amounts which progressively increase throughout the basal portion of the package and which substantially uniformly increase throughout the remainder of the package, uniformly increasing said traverse movement throughout substantially the entire package, and successively diminishing from the basal end to the tip of the package the amount of yarn or thread coiled at the tip end of the respective layers.

10. That method of winding yarn or thread into a package which consists in imparting a minimum to and fro relative traverse movement to a yarn receiver and a yarn guide for a portion only of the length of the former, in order to form the initial layer of the package, progressively shifting the path of said traverse movement along the receiver by amounts which progressively increase throughout the basal portion of the package, uniformly increasing said relative traverse movement throughout substantially the entire package, and more widely spacing the coils at the tip portion of each layer than throughout the remaining portion of such layer, whereby the number of coils at the tip portion of each layer is reduced, and the yarn or thread is quickly traversed away from the said tip into the body portion of the succeeding layer.

11. That method of winding yarn or thread into a package which consists in imparting a minimum to and fro relative traverse movement to a yarn receiver and a yarn guide for a portion only of the length of the former, in order to form the initial layer of the package, progressively shifting the path of said traverse movement along the receiver by amounts which progressively increase throughout the basal portion of the package and which substantially uniformly increase throughout the remainder of the package, uniformly increasing said relative traverse movement throughout substantially the entire package and more widely spacing

the coils at the tip portion of each layer than throughout the remaining portion of such layer, whereby the number of coils at the tip portion of each layer is reduced and the yarn or thread is quickly traversed away from the said tip into the body portion of the succeeding layer.

12. That method of winding yarn or thread into a package which consists in imparting a minimum to and fro relative traverse movement to a yarn receiver and a yarn guide for a portion only of the length of the former, in order to form the initial layer of the package, progressively shifting the path of said traverse movement along the receiver by amounts which progressively increase throughout the basal portion of the package, uniformly increasing said relative traverse movement throughout substantially the entire package while maintaining constant the period of time occupied by each traverse movement, and correspondingly decreasing the amount of yarn or thread coiled at the tip portion of the respective layers from the basal end to the tip of the package.

13. That method of winding yarn or thread into a package which consists in imparting a minimum to and fro relative traverse movement to a yarn receiver and a yarn guide for a portion only of the length of the former, in order to form the initial layer of the package, progressively shifting the path of said traverse movement along the receiver by amounts which progressively increase throughout the basal portion of the package, uniformly increasing said relative traverse movement throughout substantially the entire package while maintaining constant the period of time occupied by each traverse movement and more widely spacing the coils at the tip portion of each layer than throughout the remaining portion of such layer, whereby the number of coils at the tip portion of each layer is reduced, and the yarn or thread is quickly traversed away from the said tip into the body portion of the succeeding layer.

In testimony whereof, I have signed my name to this specification, in the presence of two subscribing witnesses.

JOHN V. CUNNIFF.
